WITNESS:

UNITED STATES PATENT OFFICE.

MEREDITH D. BRADY, OF INDIANA, PENNSYLVANIA, ASSIGNOR TO M. EDITH STEVINGS, OF INDIANA, PENNSYLVANIA.

PUSH-ROD.

1,390,272.

Specification of Letters Patent. Patented Sept. 13, 1921.

Application filed May 14, 1920. Serial No. 381,509.

To all whom it may concern:

Be it known that I, MEREDITH D. BRADY, a citizen of the United States, residing at Indiana in the county of Indiana and State 5 of Pennsylvania, have invented new and useful Improvements in Push-Rods, of which the following is a specification.

This invention relates to the operating mechanism of internal combustion engines, 10 particularly to valve operating means, and has for its object the provision of a novel push rod which is provided with screw adjusting means whereby the push rod may be adjusted for imparting to the associated 15 valve the exact movement necessary to effect proper action thereof.

An important object is the provision of a push rod of this character provided with novel locking means for holding the screw 20 in adjusted position so as to prevent dislocation and consequent derangement.

An additional object is the provision of a device of this character which will be simple and inexpensive in manufacture, highly efficient in use, durable in service, and a general improvement in the art.

With the above and other objects and advantages in view, the invention consists in the details of construction to be herein-after more fully described and claimed, and 30 illustrated in the accompanying drawings in which—

Figure 1 is a side elevation of my push rod,

Fig. 2 is a plan view, and

Fig. 3 is a longitudinal sectional view.

Referring more particularly to the drawings, the numeral 10 designates the body of the device which is cylindrical in shape and which has its lower end bifurcated, as shown 40 at 11, for the reception of a roller 12 journaled, as shown at 13. At its upper end this body is internally threaded, as shown, and is provided with a closure plug or cap 14 threaded thereinto and having a flange 15 seating upon the open end. Disposed within the body 10 is a spring 16 which has one end secured to the plug or cap 14. Threaded 45 through the plug or cap 14 is a screw 17 which is provided at its upper end with a head 18 adapted to engage the valve stem, not shown, with which the device is associated. At opposite sides this screw 17 is

formed with grooves 19. The other end of the spring 16 is secured to the lower end of the screw 17. When the screw 17 is 55 turned down the spring is naturally placed under tension tending to effect unscrewing.

In order that the screw may be locked in adjusted positions, I provide a spring-pressed plunger 20 located in the plug 14 60 and having a small plate-like handle 21 associated therewith. This plunger normally engages within either of the grooves 19 for preventing rotation of the screw.

In the use of the device it will be seen that 65 there is no departure from the use of an ordinary push rod except that means is provided for making adjustment so as to give to the valve the exact lift required. By adjusting the screw it will be seen that any 70 play between the push rod and valve stem may be eliminated so as to avoid all lost motion and produce a more quietly running motor. When necessary to take up wear or play the operator grasps the little plate handle 21 and thereby retracts the plunger 20 75 out of engagement with the screw so that the spring will cause unscrewing of the screw 17 to bring the head 18 into engagement with the valve stem and this of course 80 will effect the desired adjustment. When the handle is released the plunger will engage within a groove.

While I have shown and described the preferred embodiment of my invention, it is of course to be understood that I reserve 85 the right to make such changes in the form, construction, and arrangement of parts as will not depart from the spirit of the invention or the scope of the subjoined claims.

Having thus described my invention, I 90 claim:

1. A push rod comprising a hollow cylindrical body carrying a roller at its lower end, a plug threaded within the upper end of the body and having a threaded hole, a 95 coil spring within the body and connected with said plug whereby to hold the same against casual movement, and a screw threaded through said hole and having a head adapted to engage a valve stem to be 100 operated, the other end of the spring being connected with said screw.

2. A device of the character described comprising a hollow cylindrical body, a plug

closing the upper end of said body, a screw whereby to prevent rotation of said screw, threaded through said plug and extending and a spring within the body having one end co-axially of the body, a valve stem engaging connected with the plug and the other connected with the screw whereby to be placed 10 head on said screw, said screw being under tension when the screw is turned in 5 provided with longitudinal grooves, a spring-pressed plunger slidable laterally of one direction. MEREDITH D. BRADY.
